UNITED STATES PATENT OFFICE.

DAVID P. WILLIAMS, OF WHITNEY, NORTH CAROLINA.

INDICATOR FOR HOISTING AND CONVEYING APPARATUS.

1,156,733.

Specification of Letters Patent.

Patented Oct. 12, 1915.

Application filed November 19, 1914. Serial No. 873,067.

To all whom it may concern:

Be it known that I, DAVID P. WILLIAMS, a citizen of the United States, residing at Whitney, in the county of Stanly and State 5 of North Carolina, have invented certain new and useful Improvements in Indicators for Hoisting and Conveying Apparatus, of which the following is a specification.

This invention relates to hoisting and 10 conveying apparatus, and has for its object the provision of simple, inexpensive and efficient means whereby the engineer will be always informed of the position of the hoisting or conveying bucket and may accurately 15 control the movement of the same when the bucket itself is not within his range of vision. It frequently happens that, in the use of hoisting and conveying apparatus, the engineer or operator is so located that 20 the bucket or carriage cannot be observed by him and he is, under those circumstances, dependent upon signals given by an attendant to manipulate the engine.

It is the object of my invention to avoid 25 the delays and uncertainty occasioned by this inability of the engineer to always watch the bucket and provide means whereby the position of the bucket will be positively made known.

30 The invention also seeks to provide a device for the stated purpose which will be inexpensive to produce and maintain and which may be set up at any point within the engine room where it may be observed 35 by the operator.

The several stated objects of the invention and such other objects as will incidentally appear from the following description are attained in such mechanism as is illustrated in the accompanying drawings, and 40 the invention resides in certain novel features which will be particularly pointed out in the claims following the detailed description.

45 In the drawings, Figure 1 is a view in the nature of a diagram showing my improved indicator set up for use in connection with a two-part line; Fig. 2 is a similar view showing the device adapted to a line of 50 more than two parts; and Fig. 3 is a detail perspective view of a portion of the indicator board and parts co-operating immediately therewith.

In the drawings, 1 indicates a steam supply pipe which leads to an engine 2 utilized

to drive a hoisting drum 3 and a conveyer drum 4 which may be of any preferred construction and arranged in any desired or convenient manner. A hoisting cable 5 is secured to and coiled around the drum 3 and 60 extends from the engine room over suitable guide pulleys to the hoisting bucket in the manner which will be readily understood by those skilled in the art. In like manner a carriage-controlling cable 6 is secured to 65 and coiled around the conveyer drum 4 and extended from the engine room to the conveyer carriage in the usual manner.

In carrying out my invention, I secure to the ends of the drums 3 and 4, or to the 70 shafts supporting said drums, sprocket wheels 7 and 8 respectively, and around the said sprocket wheels I train chains 9 and 10 which extend respectively to and around sprocket wheels 11 and 12. These sprocket 75 wheels 11 and 12 are secured respectively to winding shafts 13 and 14 which are suitably mounted in any convenient manner in the engine room and are illustrated as arranged above the drums. At some convenient point 80 in the engine room, where it may be readily observed at all times by the engineer, I provide an indicator board 15 which may be one of the roof-supporting posts and is provided with two vertical series of sockets 85 or recesses 16, as shown. Upon the said indicator board 15, at or near the upper end thereof, I secure pulleys 17 and 18 around which pass cables or wires 19 and 20 which extend respectively to the shafts 13 and 14 90 to which they are secured and around which they are adapted to wind. An idler or guide 21 may be provided wherever needed to support and guide one or both of the wires so that they will pass to the respective 95 pulleys in such manner as to travel around the same easily and freely at all times. The flexible wires or cables 19 and 20 pass downwardly from the pulleys 17 and 18 to blocks 22 and 23, and then return to the respective 100 pulleys 17 and 18 and then again pass to the blocks 22 and 23 to which their ends are secured. Indicator weights 24 and 25, are suspended from the respective blocks 22 and 23 and these weights are provided with laterally projecting pointed pins or indicator fingers 26 and 27. Suitable pegs 28 and 29 are provided and are adapted to fit in any of the sockets 16, as will readily be understood.

It is thought the operation of the de- 110

scribed indicator will be readily understood. As the respective drums move in one or the other direction to wind or unwind the cables thereon, the rotation of the drums will be 5 transmitted through the described gearing to the winding shafts 13 and 14, and the cables or flexible wires 19 and 20 will, of course, be wound or unwound on said shafts. As the cables or flexible wires 19 and 20 are 10 wound or unwound on their respective shafts, the depending portions of the wires or cables will be respectively shortened or lengthened and, consequently, the indicator weights will be caused to travel vertically 15 in front of the indicator board and adjacent the vertical rows of sockets. The pegs 28 and 29 will be placed in one or another of the sockets or recesses 16, as may be determined by measurement or experiment, and 20 it is then only necessary for the engineer or operator to watch the movement of the indicator weights to be informed as to the position of the carriage and the bucket. When 25 an indicator weight has reached a position in which the pin projecting therefrom will be pointing exactly to the peg in the adjacent row of sockets, the engineer will know that the carriage or the bucket has reached the desired point of its travel and should 30 stop. Assuming that it is desired to convey a load over an excavation and lower the bucket to the bottom of said excavation which is out of sight of the engineer, the 35 engineer will drive the conveying drum 4 until the indicator weight 25 actuated thereby will bring its indicator point or pin into horizontal alinement with the adjacent peg 29. He will then know that the bucket is 40 over the point at which the load is to be deposited and will stop the movement of the conveying drum and will then set the hoisting drum in motion so as to lower the bucket to the bottom of the excavation. The indicator weight 24 operated by the hoisting 45 drum will then descend in front of the indicator board and, when the said weight brings its pin into horizontal alinement with the peg 28 in the adjacent series of recesses or sockets, the engineer will know that the 50 bucket is at the bottom of the excavation.

It is obvious that, if the conditions of use locate the engine in such a manner that the entire range of travel of the conveyer and bucket is out of the range of the engineer's 55 vision, pegs may be inserted in the indicator board to denote both limits of travel of the conveyer and of the bucket so that the engineer will, at all times, be accurately informed as to the position of both the conveyer and the bucket even though he may 60 be unable to see them. It will be readily noted that each indicator weight is positively driven by the drum to which it is respectively geared, and that the device is 65 exceedingly simple in the construction and

arrangement of its parts so that it may be readily set up in any engine room at a trifling cost.

In a cableway employing a two-part line, the load line is fastened to the tail tower 70 and the load indicator block and the load drum will remain stationary while the conveyer drum is moving the carriage. In a cableway employing a line of more than two parts, however, the load line is fastened 75 to the carriage and the load drum turns with the conveyer drum when the carriage is being shifted. In such arrangement, therefore, it is necessary to provide means for holding the load indicator stationary while 80 the carriage is being shifted, and to meet this need I have devised the arrangement illustrated in Fig. 2.

The conveyer indicator is arranged and operated in exactly the same manner as 85 shown in Fig. 1 and previously described. The load-indicator cable 19, however, is not attached to the shaft 13 but is carried past said shaft and is attached to an auxiliary shaft 30 which is mounted in swinging hangers 31. A pinion 32 is fixed on the shaft 30 and is adapted to mesh with a similar pinion 33 secured on the shaft 13 and the pinions are yieldably held in mesh by a spring 34 which is attached, at one end, to a timber 90 or some other fixed part of the engine-in- 95 closing structure and, at its opposite end, to one of the hangers 31 or otherwise arranged so that it tends to swing the shaft 30 to the shaft 13. A standard 35 is carried by a bar 100 36 which is mounted in suitable guides on the bed of the engine, or is otherwise conveniently disposed, and has one end pivoted to the lower end of an operating lever 37. The upper end of this standard projects between the shafts 13 and 30 and a brace 38 105 may be extended between the standard and the bar 36 to attain the necessary strength.

When the bucket is being raised or lowered, the pinions 32 and 33 are in mesh and 110 the auxiliary shaft will rotate at the same speed as the main winding shaft 13 so as to wind or unwind the cable 19. When the bucket has reached the desired height or depth, as shown by the indicator block, the operating lever is swung forward and the standard thereby caused to pull the shaft 30 away from the shaft 13 against the tension of the spring 34. The pinions 32 and 33 will, consequently, be disengaged and the shaft 30 115 will cease to rotate so that the load indicator block will remain at rest, the frictional engagement between the standard and the shaft under the force of the spring being sufficient to prevent the weight of the indicator block rotating the shaft. The movement of the carriage will then not affect the load indicator. When the bucket is to be again lowered or raised, the standard is 120 shifted in the opposite direction and the 125 indicator block will again be caused to rotate. The movement of the carriage will then not affect the load indicator. When the bucket is to be again lowered or raised, the standard is 130 shifted in the opposite direction and the

spring then draws the auxiliary shaft to its operative position with the pinions again in mesh.

Having thus described the invention, what is claimed as new is:—

1. An indicator for hoisting and conveying mechanism comprising an indicator board provided with indicia indicating the limit of travel of the hoisting and conveying members, shiftable devices adapted to be placed at points along said indicia to denote the points of stoppage of the hoisting and conveying members, respectively, indicator members disposed in front of the indicator board, and means for moving the said indicator members along said indicia according to the movement of the hoisting and conveying members.

2. The combination of an indicator board having a series of sockets therein, a peg adapted to be seated in any one of said sockets, an indicator movable along the line of the sockets, a drum, a winding shaft, gearing whereby the winding shaft will be actuated by the drum, and a flexible connection between the winding shaft and the indicator.

3. The combination of an indicator board having a series of sockets therein, a peg adapted to be seated in any one of said sockets, an indicator weight, a pointer projecting from said weight toward the line of sockets, a winding shaft, a flexible connection between the winding shaft and the indicator weight, a drum, and gearing whereby the winding shaft will be actuated by the drum.

4. The combination of a drum, an indicator, a shaft geared to the drum, a second shaft, a flexible connection between the indicator and the second shaft, and yieldable means for holding said second shaft in operative engagement with the shaft geared to the drum.

5. The combination of a drum, an indicator, a shaft geared to the drum, a second shaft, swinging hangers carrying said second shaft, a flexible connection between the indicator and said second shaft, a spring acting on said swinging hangers to hold the second shaft in operative engagement with the shaft geared to the drum, and means for moving said second shaft away from the shaft geared to the drum.

6. The combination of a drum, an indicator, a shaft geared to the drum, a second shaft, a flexible connection between the indicator and the second shaft, swinging hangers carrying said second shaft, a spring acting on said hangers to hold said second shaft in operative engagement with the shaft geared to the drum, a standard projecting between the two shafts and adapted to bear against the said second shaft, and means acting on said standard to move the said swinging hangers in opposition to the spring.

In testimony whereof I affix my signature in presence of two witnesses.
